Design No. 3,558, dated June 29, 1869.

DESIGN FOR A TRADE-MARK.

The Schedule referred to in these Letters Patent and making part of the same.

To all whom it may concern:

Be it known that we, H. R. DICKINSON, G. P. KINNEY, and M. F. WILSON, of Painesville, in the county of Lake, and State of Ohio, have invented certain new and useful Improvements in Design for Trade-Mark; and we do hereby declare that the following is a full and complete description of the same, reference being had to the accompanying drawings, making a part of this specification, in which the drawing represents the design, the purpose of which is to be placed upon a box, in which is packed chewing-gum, in small boxes, for sale and transportation.

A description of the design is as follows:

It is of a pictorial character, and of an oblong-square shape, having an outer border, consisting of a heavy and light line, and an inner line a short distance therefrom.

The central subject of the design is a view of a small town on the bank of a river, or other water. Near the right-hand corner is seen a small collection of houses, in the midst of which will be observed two churches or tower-like structures. At the left will be seen a collection of workshops and other buildings; also two vessels in process of construction.

Midway between the two collections of buildings referred to, is an open space of broken ground or rocks, on which stands a large irregular building, on the

central portion of which are an observatory and a flag-staff, from which the American flag is displayed.

On the water will be seen two sail-vessels, a small boat, and a raft of timber.

Immediately behind the town rises a dark, precipitous mountain, covered with patches of pine-trees. Those on the left, and nearest the buildings, are of a dark and gloomy expression. Further off in the rear, are seen other mountains, bold and precipitous, naked and bright in the sunlight; all of which makes up the background of the picture.

Immediately above the picture are the words "Alaska Chewing-Gum," while underneath the picture are the words, "A new and superior article for cleansing the teeth and sweetening the breath. Manufactured by Dickinson & Co., Painesville, Ohio;" all of which constitutes a design for a trade-mark, as above said.

What we claim as our invention, and desire to secure by Letters Patent, is—

The herein-described design for a trade-mark, substantially as described, and for the purpose set forth.
